UNITED STATES PATENT OFFICE.

WILLIBALD DUSCHNITZ, OF VIENNA, AUSTRIA-HUNGARY.

BRAKE-SHOE.

1,143,518.

Specification of Letters Patent. Patented June 15, 1915.

Application filed November 29, 1913. Serial No. 203,730.

To all whom it may concern:

Be it known that I, WILLIBALD DUSCHNITZ, a subject of the Emperor of Austria-Hungary, residing at Vienna, in Austria-Hungary, have invented certain new and useful improvements in Brake-Shoes, of which the following is a specification.

The object of this invention is to provide an efficient and silent brake-shoe which imposes less wear, on the wheel to which it is applied, than the brake-shoes heretofore known. To this end I face the shoe with felt, preferably arranged so that the ends of the fibers form the brake surface. The felt may be prepared by subjecting it to very high pressure, and may be impregnated with fatty substances, wax and like substances having a preservative effect.

The invention is illustrated in the accompanying drawing, which shows several embodiments thereof.

Figure 1 is a side-view of a brake-shoe, partly in section; Fig. 2 is a front view of the same shoe, and Fig. 3 a cross section thereof. Fig. 4 is a side view of a shoe with detachable ribs for holding the felt. Fig. 5 is a cross-section of another form of shoe, and Figs. 6 and 7 are front views, partly broken away, showing two other constructions. Fig. 8 is a perspective elevation of another construction.

Referring in the first instance to the construction shown in Figs. 1 to 3, the metal body or holder 1 is of a well known shape, with lateral ribs 2 and a central rib 4, strips of felt 3 being inserted between the ribs to afford the brake surface. The ribs are made in one piece with the body 1. But it is also possible to make the casing which surrounds the felt removable from the body 1 and exchangeable.

Fig. 4 shows a modification wherein ribs 2^a are joined to a body 1^a by dove-tail joints, the ribs in this case also serving to support felt between them.

Fig. 5 shows a modification in which a single block of felt 3^b is held between two ribs 2^b formed at opposite sides of the shoe.

Fig. 6 shows a construction in which pieces of felt 3^c are placed in cells formed by transverse ribs 4^c joining two lateral ribs 2^c of the brake-shoe.

In the construction shown in Fig. 7, cells for the felt are formed between lateral ribs

2^d and oblique ribs 4^d, the latter being somewhat curved, so that the short strips of felt have a twist. The ribs 4^d are provided with ridges 4^e for the purpose of engaging the felt, and the ridges 4^e on one side of each cell are set so as to lie between the ridges on the other side, so that there is no undue compression of the felt. The other modifications are also provided with ridges which may be running in any suitable direction.

In the construction shown in Fig. 8 a block of felt 3^e is embraced by a frame 5, which is closed tightly after insertion of the felt.

Felt is adapted to operate very efficiently as a brake surface on wheel treads of iron and steel, especially if the ends of the fiber form the brake surface. The durability of the felt may be increased by compression thereof after the usual process of fulling, a high pressure, say of 200 kg. per cm.² being used. After being thus compressed the felt should be inserted into the cells, grooves or frame of the brake-shoe of which it is to form part, before it has been able to expand again. The subsequent expansion then gives the felt a very firm hold in the shoe, and also causes it to bulge out slightly at the face of the brake.

Fatty substances, wax or the like used for impregnation of the felt increases the durability thereof and serves to prolongate its life. The impregnation may take place before or after compression of the felt.

What I claim as my invention and desire to secure by Letters Patent of the United States is:—

A brake-shoe of the character described, comprising in combination, a holder having side flanges, ribs connecting said flanges for forming cells with the same, a facing of highly compressed felt in each of said cells constituting the brake face of the shoe, and a plurality of ridges alternately arranged at the lateral faces of said ribs for holding the felt in said cells.

In witness whereof I have signed this specification in the presence of two witnesses.

WILLIBALD DUSCHNITZ.
